UNITED STATES PATENT OFFICE.

WILLIAM H. CHENEY, OF ST. LOUIS, MISSOURI.

LOCOMOTIVE ASH-PAN.

994,817.

Specification of Letters Patent. Patented June 13, 1911.

Application filed February 14, 1910. Serial No. 543,895.

To all whom it may concern:

Be it known that I, WILLIAM H. CHENEY, a citizen of the United States, and resident of St. Louis, Missouri, have invented certain new and useful Improvements in Locomotive Ash-Pans, of which the following is a specification containing a full, clear, and exact description, reference being had to the accompanying drawings, forming a part hereof.

My invention relates to improvements in locomotive ash pans, the object of my invention being to construct an improved ash pan for locomotives which will eliminate the annoyances and dangers incident to warping caused by the heat of cinders and ashes carried thereby, and which ash pan is provided with suitable track for the support of a wheeled bottom, and track which bottom is so isolated with relation to the ash pan that hot cinders or ashes carried by the pan are prevented from warping said track and falling from the ash pan.

A further object of my invention is to provide an improved locomotive ash pan with cooling webs at its sides for supporting wheel-tracks, whereby the bottom of the hopper will be carried by wheels running upon said tracks, and the tracks themselves will be kept cool and prevented from warping.

For the above purposes my invention consists in certain novel features of construction and arrangement of parts as will be hereinafter made clear, pointed out in the claim and illustrated by the accompanying drawings, in which:

Figure 1 is an elevation illustrating a portion of a locomotive fire box, the ash pans carried by the fire box and my improved attachments carried by the ash pans together with the means for operating the sliding bottoms for the ash pans; Fig. 2 is a plan partly in section taken on the line 2—2 of Fig. 1; Fig. 3 is an enlarged rear end elevation illustrating a portion of the fire box, one of the ash pans and my improved hopper and parts carried thereby; Fig. 4 is an enlarged, sectional elevation taken on the line 4—4 of Fig. 1; and Fig. 5 is a longitudinal, sectional elevation taken on the line 5—5 of Fig. 4, the sliding bottom and parts carried thereby being shown in dotted lines in an open position.

Referring by numerals to the accompanying drawings: 1 designates the locomotive

fire box and 2 the ash pans carried by the fire box. The ash pans are of the usual construction, being made up of sheet metal, that is they are constructed of the same general 60 conformation as the ordinary ash pan and are somewhat shorter from top to bottom than the ordinary ash pans.

Carried by the ash pans and preferably secured thereto by bolts or rivets 3 are the 65 cast iron hoppers 4 and 5, each being a counterpart of the other, the hopper 4 being secured to the forward ash pan and the hopper 5 being secured to the rearmost ash pan. The end walls 6 of the hoppers converge from 70 top to bottom while the side walls 7 of the hoppers are substantially vertical. Projecting laterally from the outside faces of the walls 7 and of a length approximating the length of the hoppers are the webs 8. The 75 hopper complete together with said webs 8 are preferably cast in one piece. Secured to the side faces of the webs 8 are the tracks 9 which are of a length greater than the webs and project laterally beyond said webs. 80 The upper faces of the tracks are in a plane above the upper faces of the webs 8 for purposes hereinafter made clear.

10 and 11 designate the sliding bottoms for the hoppers 4 and 5 respectively, each 85 of which bottoms is provided with hangers 12, there being two hangers on each side of each bottom. The hangers, as shown in Fig. 4 of the drawing, are preferably constructed of a single piece of material and comprise 90 a portion arranged to be secured to the bottom face of the bottom which extends outwardly some considerable distance from the side of the bottom. From thence the piece is bent upwardly approximately at right 95 angles to the portion which is secured to the lower side of the bottom. The upright portion is curved inwardly and extends downwardly parallel with the upright portion and said parallel portions are provided with 100 coinciding bearing openings through which the journals 13 are inserted and held against longitudinal movement. Each of the journals 13 supports a flanged wheel 14 which 105 wheels are designed for travel upon the tracks 9 with their flanges inside of said tracks.

The bottoms 10 and 11 are provided with upwardly projecting side walls 15 which embrace the walls 7 of the hoppers and the 110 bottoms are preferably of a length greater than the length of the bottom portion of the

hopper as shown in Fig. 5, thereby forming a ledge 16 at the forward end of each bottom to catch and hold ashes or cinders which may be discharged from the ash pan. At 5 the end of the bottom opposite the ledge 16 are the right-angled extensions 17 of the walls 15 and as shown in Fig. 3 the extensions 17 are reduced at 18 and the reduced portion 18 is provided with an inclined face 10 19 designed to hold and receive cinders and ashes that may be discharged rearwardly from the ash pan.

The extensions 17 form a stop to limit the forward movement of the bottoms, the rearward movement of the bottoms being limited by engagement of the hangers 12 with the outer ends of the cross rod 20 carried by the rear ends of the tracks 9. The bottom 11 at its rearmost end is provided with a per- 15 forated ear 21 which projects downwardly from the bottom face of the bottom and is arranged at the approximate transverse center of the bottom. Pivoted connected with the ear 21 is a link 22 and connected with 20 the link is a lever 23, the upper end of which lever projects through the deck of the cab where it may be within easy reach of the operator. At the forward end of the bottom 11 and projecting downwardly from 25 the rear face thereof and located adjacent the sides 15 are the perforated ears 24. The forward bottom 10 is provided with perforated ears 25 arranged adjacent the sides of the bottom, and, like the ears 24 of the bottom 11 project downwardly from the bottom face of the bottom. The ears 25 are arranged adjacent the rear end of the bottom 10. Connecting the ears 24 of the bottom 11 with the ears 25 of the bottom 10 are the 30 40 connecting links 26.

I am aware that heretofore the sheet metal ash pans of locomotives have been provided with hoppers and that such hoppers have been constructed of heavier material than the ash pans. These hoppers are usually formed hollow for the purpose of introducing steam for thawing or preventing freezing of the contents of the ash pans and hoppers, but I believe the cast metallic ash pan, 45 as shown, with such a longitudinal web is new. It is to be understood that such hoppers must withstand great heat and consequently rapid variations of heat as for instance when the hot ashes or cinders are 50 emptied and rapidly cooled, thus it is obvious that the ordinary hopper and ash pan is subject to warping. The construction of the hopper, as shown with the reinforcing web 8, is practically non-warpageable and due 55 to the novel construction of sliding bottom for the hopper, the dropping of live coals or cinders when the locomotive is in motion is 60 eliminated.

In practical operation, assuming the parts 65 to be assembled as shown, it is obvious that

ashes and cinders discharged from the grates within the fire box will fall, by gravity, into the pans and be held and carried in the hoppers. To persons familiar with the art, it is obvious that such ashes and cinders must 70 not be discharged promiscuously upon the road-bed for the reason that the cross ties or bridge timbers of such road-bed would be burned and, perhaps, entirely destroyed by fire from such live coals or cinders. It is 75 to be noted that the sliding bottoms project some slight distance in advance of the bottom portions of the hopper, thus making a ledge upon it to carry live coals or ashes discharged from the hopper, and it is to be 80 noted that at the opposite ends of the bottoms there is an inclined face for carrying live coals or ashes that might be discharged from the hoppers. In order that the sliding bottoms may freely move into either open or closed positions relative to the hoppers, it is 85 essential that the hoppers and engaging parts of the bottoms be so constructed as to not be easily warped out of shape. Such warping is eliminated by forming the walls 90 of the hopper of considerable thickness and reinforcing such walls by the webs. The webs 8 not only serve to reinforce the side-walls of the hopper to prevent warping but serve as a support for the tracks upon which 95 the bottoms are moved. When it is desired to empty the hoppers and pans, it being understood, to persons familiar with railroad- 100 ing, that such discharges are made at points where ash pits are located for this purpose, one of the operators of the locomotive, either the fireman or the engineer, will grasp the lever 23 within the cab of the locomotive and by manipulation of the lever draw the bottoms 10 and 11 rearwardly. The movement of the bottoms is limited in a rearward direction by the engagement of the rearmost hangers 12 with the projecting ends of the cross rod 20 connecting the tracks at their rear ends. Thus, it is obvious that the hopper is wholly open and that the contents 110 thereof will be rapidly discharged. To close the hoppers the motion of the lever 23 is reversed and the bottoms 10 and 11 are moved forwardly until the portions 17 of the walls 115 of the bottom engage with the rear faces of the lower ends of the hoppers.

I claim:

In a locomotive ash pan, the combination with a sheet metal hopper-shaped ash pan proper, of a cast metallic hopper, the side walls of which are vertical and the front and rear walls inclined for the greater portion of their lengths, the hopper having vertical walls at its bottom end, a bottom for the hopper having vertical side walls embracing the side walls of the hopper, said bottom being of greater length than the hopper, integral webs projecting laterally from the side walls of the hopper, tracks secured 120 125

to said webs, hangers secured to said bottom, rollers on said hangers arranged to ride upon said tracks, means carried by said trucks for engagement with said hangers to limit the movement of the bottom in one direction, and an inclined lip at the rear end and on the upper face of said bottom to serve the double function of a stop to limit the forward movement of the bottom and to carry live coals which may discharge from the hopper between the lower margin of

the hopper and the upper face of the bottom, substantially as shown and for the purposes stated.

In testimony whereof, I have signed my ¹⁵ name to this specification, in presence of two subscribing witnesses.

WILLIAM H. CHENEY.
